BROADCAST SYSTEM

Rudolf Seidelbach, Berlin-Mariendorf, Germany,
assignor to C. Lorenz Aktiengesellschaft, Berlin-Tempelhof, Germany, a German company

Application March 31, 1936, Serial No. 71,831
In Germany April 6, 1935

6 Claims. (Cl. 179—2.5)

It is well known in connection with the so called subscriber-broadcast to transmit several programmes simultaneously over telephone networks by means of different waves, namely three different waves at the present. In order to ensure a high efficiency of transmission the subscriber lines must be subject to certain measures on the transmitting side. In this connection, however, difficulties are encountered since the subscriber lines are very different in length. There are also difficulties due to the number of subscriber lines being liable to variation. In a practical example of an automatic exchange, 60% of the lines is not longer than 3 kilometers and 30% not longer than 5 kilometers, the remainder varying between 5 and 15 kilometers in length. In such case the measure to which the lines are subject may consist in combining them to form groups in accordance with these lengths and to connect them in parallel on the exchange side and further to employ transformers for coupling them to the transmitting arrangement. The primaries of such transformers may be connected in series to the high frequency generator. The disadvantage of this arrangement is that a mutual independency of the groups cannot be attained. On the contrary, variations of the surge impedance of one group or other will influence the surge impedance of the other groups, this being troublesome especially if the number of subscribers, that is, the number of connected lines is frequently varied. The simplest way would be to combine the lines to form groups and then to make these groups equal to each other by arranging artificial means of attenuation. This mode however would entail that very much energy would be destroyed. For, as will be seen from the numerical example before stated, most of the subscriber stations are comparatively near to the telephone exchange. The attenuation of all these lines would have to be augmented to be of the same value as the attenuation of the longest subscriber line connected to the exchange, a mode which of course would involve a great loss of energy.

In order to avoid these disadvantages the invention proposes to combine the subscriber lines to form groups in the manner indicated and to allot additional high frequency amplifiers to such groups.

The invention is described hereafter with reference to the accompanying drawing in which by way of example a circuit arrangement is shown which is adapted for effecting the invention.

Three high frequency transmitters are denoted by I, II, III. By Gr_1 , Gr_2 , Gr_3 three groups of subscriber lines L are designated. In order to suit the surge impedance of these lines to the transmitter, transformers are used in connection with all the transmitters, the different voltages required in accordance with the different wave lengths being maintained by the transmitters themselves. Group Gr_1 is connected to transmitter I by a transformer 4. The transmitters II, III are likewise connected to group Gr_1 , namely by transformers 5, 6. With respect to the groups Gr_2 , Gr_3 , transformers 7, 8 are provided. Connected in parallel with the transformers 7, 7', 8 are potentiometers 9, 10, 9', 10', 15 11, 12. The potentials derived from 9, 10, 9', 10', 11, 12 are conveyed to additional high frequency amplifiers 15, 16 to which the groups Gr_2 , Gr_3 are attached by transformers 13, 14. The connections between potentiometers 9, 10' and amplifiers 15, 16 are not shown in the drawing. These potentiometers, however, are assumed to be connected in the same manner as potentiometers 9, 10. The input circuits of the amplifiers 15, 16 are connected to the transmitters II, III by 20 means of the transformers 7, 8 and potentiometers 9 to 12, and in such a manner that the voltages required for the respective wave lengths are produced. The surge impedance of the lines L in this case is rendered suitable by means of 25 the transformers 13, 14 which are located in the output of the amplifiers 15, 16. By 17, 18 filters are denoted.

The advantage of the novel circuit arrangement is that no energy losses occur and that the 35 regulation of the surge impedance of the several groups of lines has no influence on the surge impedance of other groups.

For the sake of clearness the arrangement represented nearly contains the high frequency 40 portion, that is, does not contain the low frequency exchange portion and the like. The high frequency exchange arrangement and the low frequent one are separated from each other by filters in a manner well known in itself. The 45 respective details need not be described here since they are known per se.

What is claimed is:

1. A broadcast system comprising a plurality of high frequency transmitters, a plurality of 50 subscribers' lines combined to form groups having comparatively similar lengths and impedances, a separate coupling path between each of these groups and said plurality of transmitters, an individual amplifying device connected in one 55

- or more of said separate paths whereby a desired intensity of signal is produced at the far end of every line, and impedance matching means between said transmitters and said lines.
5. 2. In a wired program broadcast system, a plurality of high frequency transmitters, a plurality of subscribers' lines of different characteristics associated in groups, within each of which, the lines are of substantially similar characteristics,
- 10 an individual coupling path from said plurality of transmitters to one of said groups of lines, further individual coupling paths from said plurality of transmitters to each other group of lines, impedance matching means in each of said
- 15 paths and an individual amplifier connected in each one of said further paths and adapted to amplify the power in said one of said paths to such a level relative to the power in the other paths, that the resulting power transmitted to
- 20 the ends of all lines is substantially the same.
3. A system according to claim 1, further comprising potentiometers disposed between said individual amplifying devices and said transmitters.
4. A system according to claim 1, wherein the output circuit of said individual amplifying devices is suited to the surge impedance of the subscriber lines.
5. A system according to claim 1, further comprising filters adapted to prevent high frequency energy from passing from one transmitter to another.
6. In a broadcast system the combination of high frequency transmitters with telephone-
10 subscriber lines combined to form groups having comparatively similar lengths and impedances, means connecting these groups to said transmitters, a high frequency amplifier individually coupled to each one of said groups, an additional group of telephone-subscriber lines fed directly from said transmitters without the interposition of such an individual amplifier, connections from one or more of said high frequency transmitters to the latter group, and means for matching the
15 output circuits of these transmitters to the surge impedance of said last mentioned group of lines.
